MOLDED PULP EGG TRAY

Joseph B. Fleming, Jr., and Floyd H. Porter, both of Dallas, Tex., assignors to Fleming & Sons, Inc., a corporation of Texas

Filed Nov. 5, 1964, Ser. No. 82,536

Term of patent 14 years

(Cl. D58—13)

FIG. 1

FIG. 2

FIG. 3

FIG. 4

FIG. 1 is a plan view of a molded pulp egg tray showing our new design,

FIG. 2 is a side elevational view, partly in section, taken on the line 2—2 of FIG. 1,

FIG. 3 is a side elevational view, partly in section, taken on the line 3—3 of FIG. 1, and

FIG. 4 is a cross-sectional view taken on the line 4—4 of FIG. 1.

We claim:

The ornamental design for a molded pulp egg tray, as shown.
